UNITED STATES PATENT OFFICE.

JOHN EDWARDS, OF HOMESTEAD, JOHN R. DAVIES, OF DUQUESNE, AND JOHN JARRETT, OF PITTSBURG, PENNSYLVANIA.

DRAFT-RIGGING.

SPECIFICATION forming part of Letters Patent No. 614,262, dated November 15, 1898.

Application filed January 28, 1898. Serial No. 668,279. (No model.)

To all whom it may concern:

Be it known that we, JOHN EDWARDS, of Homestead, JOHN R. DAVIES, of Duquesne, and JOHN JARRETT, of Pittsburg, in the county 5 of Allegheny and State of Pennsylvania, have invented a new and useful Improvement in Draft-Riggings, of which the following is a full, clear, and exact description, reference being had to the accompanying drawings, forming part of this specification, in which—

Figure 1 is a partial longitudinal section of the end of a car, showing our improved rigging in position. Fig. 2 is a bottom plan view of the same, partly broken away. Fig. 3 is 15 a front elevation. Fig. 4 is a transverse section on the line IV IV of Fig. 1; and Fig. 5 is a detail perspective view, showing one of the draft-irons.

Our invention relates to the draft-riggings 20 of railway-cars, and is designed to provide a device of this character which shall be simple and cheap of construction, in which the strain, whether of tension or compression, shall be equalized and distributed on opposite sides of the draw-bar, and in which the parts can be easily removed and replaced.

In the drawings, 2 2 represent the draft-timbers of a car, and 3 3 two Z-bars, the upper flanges 4 of which fit in suitable recesses 30 in the upper faces of the draft-timbers. At their front ends these Z-bars are cut down, so as to form a lateral flange or lug 5, which is secured to the draft-timber by a bolt 6. Near their front ends the lower depending 35 portions of the Z-bars are slotted horizontally at 7 to receive a transverse connecting-bar 8, which passes through these slots and through slots in the U-shaped strap 9, which encircles the rear end of the draw-bar 10. Surrounding the end portions of the bar 8, outside the draft-timbers, are the yokes 11 40 11, secured to the rearwardly-extending rods or stems 12, which pass through the cross-timber 13. Between this cross-timber and the straps or yokes 11 and surrounding the rods 12 are springs 14, and in the rear of the timber are the similar springs 15, which abut at one end against the timber and at the other against keys 16 in the rods. The bar 8 is 45 provided at one end with a head 17, and when it is slipped into place it is secured by a key

18, driven through a slot in its other end. The cross piece or timber 13 passes through slots 19 in the draft-irons and when in place is secured by the bolts 20. When these draft-irons are put in position between the draft-timbers, the spacing-block 21 is driven into place between them and secured by the through-bolts 22.

The rear ends of the Z-bars are slotted, as 60 shown at 23, and a strap 24 extends across their rear ends, within the slots, this strap being held in place by a block 25, fitting in a recess in cross-sill 26 and into the recesses of the Z-bars, this block being held in place 65 by any suitable means.

To assist in taking up compressive strain, we preferably provide the draw-bar 10 with inclined edge faces 27, against which blocks 28, having correspondingly inclined faces, 70 are yieldingly pressed by a bolt 29, extending through the slot in the draw-bar. The springs are held within suitable sockets 30, and when the buffing action occurs the blocks, riding up the inclines, will cushion the blow and take 75 up the strain.

In the operation of the device when a pulling strain is exerted upon the draw-bar the rods 12, being pulled forwardly, will compress the springs 15 and drive the blocks 28 up the 80 inclined faces of the draw-bar, the strain thus being equalized and distributed upon both sides. Similarly, in buffing, the rods being moved rearwardly will compress the springs 14, the strain being distributed as before. 85

The advantages of our invention will be apparent to those skilled in the art, since the rigging is of few parts, which parts are simple and can be cheaply made, while the strains 90 are evenly and uniformly distributed, thus preventing liability to injury of the rigging. The draft-irons may be easily and quickly removed and replaced without tearing up the floor of the car, and any of the other parts 95 of the rigging may be easily replaced by removing the block 25 and disconnecting the parts.

Modifications in the form, construction, and relative arrangement of the parts of the device may be made by those skilled in the art 100 without departure from our invention, since

What we claim as new, and desire to secure by Letters Patent, is—

1. In a draft-rigging, the combination with draft-timbers, of draft-irons consisting of a pair of Z-bars having their upper flanges lying on the top of the draft-timbers, and a spacing-block secured between the draft-irons and the timbers, substantially as described. 50
10. 2. In a draft-rigging, the combination with draft-timbers, of a pair of Z-bars having their upper flanges lying on the top of the draft-timbers, and a cross-piece extending through slots in the Z-bars and secured to the bases of the draft-timbers, substantially as described. 55
15. 3. In a draft-rigging, a pair of plates having upper flanges lying on top of the draft-timbers, a draw-bar movable between the same, a transverse bar connected to the draw-bar and extending through slots in the plates, and springs connected to the end portions of said transverse bar, substantially as described. 60
20. 4. In a draft-rigging, draft-irons consisting of a pair of Z-bars, and draft-timbers having top recesses for their upper flanges, substantially as described. 65
25. 5. In a draft-rigging, the combination with draft-timbers, of a pair of Z-bars having their top flanges lying on the draft-timbers, each Z-bar having a lateral lug secured to the base of the end sill, substantially as described. 70
30. 6. The combination with a pair of slotted draft-irons, of a draw-bar between the same, a removable cross-bar extending through slots in the draft-irons and secured to the draw-bar, and rods detachably secured to the cross-bar and having coiled springs thereon, substantially as described. 75
35. 7. The combination with a draw-bar, of a transverse bar secured thereto, rods having straps or yokes detachably secured to said transverse bar, and coiled pulling and buffering springs surrounding said rods, substantially as described. 80
40. 8. In a draft-rigging, the combination with
- oppositely-located draft-irons, of a cross-timber passing through slots in the same and secured to the car-framing, rods extending through this timber on opposite sides of the draft-irons and connected to the draw-bar, and coiled springs surrounding the rods upon each side of the cross-timber, substantially as described. 85
9. In a draft-rigging, the combination with a draw-bar, of a transverse bar secured thereto and extending through slots in plates secured to the timbers at each side of the draw-bar, and rods having straps surrounding the transverse bar, said rods being provided with springs, substantially as described. 90
10. In a draft-rigging, the combination with the oppositely-located Z-bars, of a spacing-block secured between the same, and a strap arranged to hold their rear ends and entering slots therein, substantially as described. 95
11. In a draft-rigging, the combination with a draw-bar, having inclined faces at its opposite edges, of spring-pressed blocks bearing upon said face, and a bolt connecting the blocks and extending through a slot in the draw-bar, substantially as described. 100
12. In a draft-rigging, the combination with draft-timbers, of draft-irons consisting of plates which extend along the inner faces of the draft-timbers and line them, said plates having upper lateral flanges secured to the upper portions of the timbers, substantially as described. 105

In testimony whereof we hereunto set our hands.

JOHN EDWARDS.
JOHN R. DAVIES.
JOHN JARRETT.
